UNITED STATES PATENT OFFICE.

ALEXANDER W. BIDDLE, OF PHILADELPHIA, PENNSYLVANIA.

GOLF-CLUB.

1,000,982.

Specification of Letters Patent. Patented Aug. 22, 1911.

Application filed June 1, 1910. Serial No. 564,422.

To all whom it may concern:

Be it known that I, ALEXANDER W. BIDDLE, of Philadelphia, in the county of Philadelphia and State of Pennsylvania, have invented certain new and useful Improvements in Golf-Clubs, whereof the following is a specification, reference being had to the accompanying drawings.

In said drawings, Figure I, represents a front view in elevation of the head, or lower end, of a golf club, embodying a preferred form of my invention, the shaft being only partially indicated. Fig. II, represents a plan view of the under side of the head. Fig. III, is a transverse section through the head, on the line III, III, of the other figures, showing also a golf ball of normal size in juxtaposition with the front face of the head.

My invention has peculiar value for clubs of the type usually termed "brassies", whose construction and purpose are well known to golfers, and I have therefore illustrated the improvement in such an embodiment.

The object and specific utility of the invention can be best stated after the description thereon, which I shall now proceed to give.

In the drawings, 1, represents the lower portion of the shaft of the golf club, and 2, the head thereof, the remaining portion of the shaft not being shown, since its construction is well understood. The head may be made of wood, as is usual in clubs of this type.

3, indicates the front or striking face of the club, which, as shown in Fig. III, is rearwardly inclined at that portion which is normally intended to make contact with the ball 4, in the act of striking.

The sole, or lower portion of the club is shown as provided with a metal plate 5, which, throughout its main extent, has substantially the flat surface and other characteristics of the plate used in ordinary brassies, but along the lower portion of the front, where the sole merges into the striking face, said metallic plate (and correspondingly the wooden portion of the head in contact with the same), is definitely rounded as indicated at 6. The rounding of the face is prolonged upward to a substantial distance above the plane of the sole, preferably extending nearly to the point at which contact with the ball occurs in normal strik-

ing. The metallic plate 5, may be secured to the head by means of screws 7, in the usual manner.

The object of the invention and the specific advantages thereof, are briefly as follows: Ordinarily in clubs of this class, the front face and the sole are both substantially plane surfaces and meet at a distinct angle, so that a definite edge is presented along the region where they come together, this edge being present even though, as is sometimes the case, the front portion of the metallic plate is filed smooth. In other words, the metallic plate is substantially flat through its entire extent, and does not embrace the wood of the club in an upward direction along the lower portion of the front face. The result is that when such a club is used, for instance, in deep grass, the front edge has a tendency to be caught by the grass, so that the force and accuracy of the stroke are impaired. So also, even in playing from what is termed a "good lie", if the ground be struck, or "schlaffed", by the club, the relatively sharp front lower edge tends to dig into the earth and cause the club to trip, so that the stroke is checked and the direction is deflected. By definitely rounding the region where the face merges into the sole and prolonging said rounded portion upward to a substantial distance, I have found that a most surprising advantage may be obtained in avoiding such difficulties as are above stated. The club will slip through relatively thick grass without entanglement or deflection, and in the case of striking the ground in rear of the ball, will slide along the surface without tripping, so that even in the hands of inexperienced golfers, the accuracy and force of the stroke can be maintained under circumstances where with an ordinary brassie, the tendency to impairment would be very marked.

I have described and shown the invention in what I believe to be its most desirable embodiment, both as to details of structure and extent of rounding, but it must be understood that I do not limit myself to the exact form or proportions shown and described, nor do I consider it absolutely essential that when a metallic plate is used, it should be upwardly prolonged to the extreme limit of the rounded portion, although I deem such prolongation desirable, in that

the face of the club (when wood is the material employed), is thereby better protected against bruising and splintering.

- Having thus described my invention, I
- 5 claim:
1. A golf club of the brassie type having a flat sole and a definitely rounded portion extending along the region where the front face merges into the sole, said rounded portion being prolonged upward to a point below, but substantially near to the region of normal contact between the front face and the ball in the act of striking; the sole and rounded portion being provided with a metallic plate whose front edge is extended upon and conforms to the face of said rounded portion.
  - 10 2. A golf club of the brassie type having a flat sole and a definitely rounded portion extending along the region where the front
  - 15

face merges into the sole, said rounded portion being prolonged upward to a point below, but substantially near to the region of normal contact between the front face and the ball in the act of striking; the sole and rounded portion being provided with a metallic plate whose front edge is extended upon and conforms to the face of said rounded portion.

In testimony whereof, I have hereunto signed my name at Philadelphia, Pennsylvania, this thirty-first day of May, 1910.

ALEXANDER W. BIDDLE.
